Patented Mar. 20, 1917.

John Deinami ^{INVENTOR}
Howard P. Deinami ^{ATTORNEY.}

UNITED STATES PATENT OFFICE.

JOHN DAMIANI, OF SYRACUSE, NEW YORK.

LOCK.

1,219,707.

Specification of Letters Patent. Patented Mar. 20, 1917.

Application filed November 27, 1916. Serial No. 133,628.

To all whom it may concern:

Be it known that I, JOHN DAMIANI, a subject of the King of Italy, and resident of Syracuse, in the county of Onondaga, in the State of New York, have invented new and useful Improvements in Locks, of which the following, taken in connection with the accompanying drawings, is a full, clear, and exact description.

10 This invention relates to certain improvements in locks, particularly adapted for use in the manufacture of safes and the like, usually embodying locks of the combination type.

15 The primary object of the invention is to produce an efficient combination lock for the purpose described while obviating the use of tumblers and the like which necessarily cause a noise sufficient to be detected when 20 falling into place as the operating means is moved even by one not aware of the combination. Skilled persons, by listening to the falling of the tumblers, are able to determine the combination and operate the 25 locking mechanism to open the safe. The structure of this invention, while requiring the exact adjustment of certain members in accordance with a pre-determined combination, obviates the use of the member, the 30 movement of which would disclose the combination for unlocking the safe and requires an accurate and detailed knowledge of the combination before the bolts of the lock can be withdrawn from locking position.

35 Other objects relate to the specific features of construction and arrangement and will more fully appear from the following description taken in connection with the accompanying drawings in which—

40 Figure 1 is a front elevation of a portion of a safe embodying this invention.

Fig. 2 is a vertical cross section of the same illustrating the bolts in locking position, the figure being slightly reduced in size 45 as compared with Fig. 1.

Fig. 3 is a view similar to Fig. 2 showing the bolts as withdrawn from locking position.

Fig. 4 is a cross section on line 4—4, Fig. 50 1 and at substantially right angles to the sections of Figs. 2 and 3.

The safe, a portion of which is shown, may be of the usual construction and embodies an inclosing wall —1— and a suitable 55 door —2—. The door —2— is adapted to carry and contain the locking mechanism

hereinafter described. The door embodies a main wall —3— and a secondary wall —4— as secured to each other and spaced apart by plates —5— and —6—, as shown, 60 the plate —5— being formed integrally with the main wall —3—, whereas, the plate —6— is removably secured to said wall as by screws —7—. The plates —5— and —6— are placed apart a short distance and 65 lie in substantial parallelism horizontally of the door. The bolts —8— and —9— are slidably mounted on the main wall —3— as by means of clamps —10— and are adapted to move through the vertical portion of said 70 wall and to seat themselves in recesses —11— and —12—, respectively, in the inclosing wall —1— of the safe to lock door —2— against opening.

For the purpose of preventing operation 75 of the bolts except by one aware of the necessary combination, the bolt —9— is formed with a series of cam surfaces —13—, in this particular illustration, four in number, arranged to contact with the ends of a series 80 of dogs —14— slidably mounted in aligned openings in the plates —5— and —6—, the lower end of each dog being shaped to conform to the cam surfaces —13—, whereby, reciprocal movement of the bolt will effect a 85 reciprocal movement of the dogs, as shown, at substantially right angles to the movement of the bolt. Each dog is provided with a flange —15— normally held in contact with the plate —5— by a spring —71—, the 90 springs acting to return the dogs to their limit of downward movement after each forced movement due to the reciprocation of bolt —9—.

A series of disks —16— are provided, one 95 for each dog, having their peripheries normally lying in substantial contact with the end of the adjacent dog to prevent reciprocation of said dog, thereby preventing movement of bolt —9—. Each disk is, however, 100 provided with a peripheral recess 17 of a size adapted to receive the adjacent end of its dog, when the disk is moved to bring its recess into exact registration with the end of the dog and for this purpose the disks are 105 mounted on shafts —18— and are keyed or otherwise secured thereto and are held thereon as by nuts —19—. The disks may be spaced from the adjacent wall —3— by 110 dished washers —20—. The shaft —18— extends through the wall —3— of the door and is mounted thereon outside the door, a

suitable dial —21— rotating with the shaft in like manner as the disk —16—. The shaft terminates in a suitable knob or handle —22— for rotating the dial —21— and the disk —16— so that by moving the dial —21— to a pre-determined position, the disk —16— will be moved to bring its respective recesses in registration with the adjacent dog —6—.

10 In this specific illustration four disks, four dials, four dogs and four cam surfaces are illustrated requiring a combination of four numbers or other indicia, one for each dial, in order that all of the disks may be moved into proper position to permit the movement of bolt —9— to release the locking mechanism. The bolts —8— and —9— are adapted to be operated by a suitable handle —23— external of the safe and 20 adapted to operate a shaft —24— having a bar —25— secured thereto, which bar has its opposite ends positioned in recesses —26— and —27— formed in bolts —8— and —9— respectively and preferably the recess —27— 25 in bolt —9— is closed by plate —28— removably secured to the bolt.

The operation of the lock will be readily understood. One knowing the combination can move each of the series of dials to a 30 proper position to bring the respective disks —16— rotating therewith into proper position to permit movement of the adjacent dog into the peripheral recess of the disk thereby permitting reciprocation of bolt 35 —9— through the medium of bar —25— operated by the usual handle —23—. The safe can neither be locked nor unlocked without an accurate and detailed knowledge of the combination, the dogs being held at 40 all times by the springs —6— and disk —16— in the line of movement of the bolt —9—, the flanges —15—, however, limiting the movement of the dogs toward the bolt.

It will be readily apparent that various 45 changes may be made in the details of construction and arrangement without depart-

ing from the spirit of this invention as set forth in the appended claims.

What I claim is:

1. A safe comprising a main wall, a movable door, a pair of bolts slidably mounted on the door, a bar for simultaneously operating both bolts, a handle outside the safe for operating said bar, one of said bolts provided with a plurality of cam surfaces, 55 a pair of substantially parallel plates adjacent the bolt, said plates having aligned openings, a plurality of dogs mounted in said openings and having ends respectively in contact with said cam surfaces, springs between said plates for holding the end portion of the bolts in contact with said cam surfaces, a plurality of rotary disks, one for each dog, each disk provided with a peripheral recess for receiving the end of the 60 adjacent dog, a dial for each disk and means outside the safe for rotating the disks.

2. In a lock, a series of disks having peripheral recesses, a series of slideable dogs having ends formed to seat in said recesses, 70 springs normally holding the dogs out of the recesses, and a bolt having a plurality of cam surfaces for moving said dogs against the tension of their springs into said recesses when registered therewith to permit retraction of the bolt.

3. In a lock, a series of disks having peripheral recesses, a series of slideable dogs having ends formed to seat in said recesses, 80 springs normally holding the dogs out of the recesses, a bolt having a plurality of cam surfaces for moving said dogs against the tension of their springs into said recesses when registered therewith to permit retraction of the bolt, and knobs and dials in connection with said disks.

In witness whereof I have hereunto set my hand this 18th day of November, 1916.

JOHN DAMIANI.

Witnesses:

E. A. THOMPSON,
BERTHA N. SWART.
